CAR WHEEL TRUING BRAKE SHOE

Filed Jan. 18, 1938

UNITED STATES PATENT OFFICE

2,161,363

CAR WHEEL TRUING BRAKE SHOE

Charles A. Malcolm, Meadow Bridge, W. Va., assignor of one-sixth to J. H. Bowles, one-sixth to Modie Walker, and one-sixth to A. C. Clifton Walker, all of Cabin Creek, W. Va.

Application January 18, 1938, Serial No. 185,612

2 Claims. (Cl. 188—245)

This invention relates to brake shoes for car wheels and particularly to certain improvements in the brake shoe forming the subject-matter of my Patent No. 972,202. The general object of this invention is the same as stated in my prior patent, namely, to provide a brake shoe which shall automatically true the periphery of a car wheel to which it is applied and which includes an abrading block and a brake shoe proper or block holder in which the abrading block is detachably supported.

The particular object of the present invention is to so form the abrading or truing block and the shoe which supports it that the abrading block may be used until only a very small amount of the block is left, thus permitting long usage of the block and thus reducing the cost of these blocks, and a further and very important object is to form the abrading block in longitudinally extending sections so that sections of different hardness may be used or sections having different abrading qualities may be used to suit any particular condition of the wheel upon which the block is to be applied.

A further object is to provide a block which is so constructed that it may be used for abrading and truing the flange of the car wheel.

Other objects will appear in the course of the following description.

My invention is illustrated in the accompanying drawing wherein:

Fig. 1 is a fragmentary elevation of a portion of a car wheel with my brake shoe applied thereto.

Fig. 2 is a section on the line 2—2 of Fig. 1.

Fig. 3 is an elevation of the brake shoe and the abrading block by itself showing in dotted line the manner in which the block wears.

Fig. 4 is a perspective view of the brake shoe by itself.

Fig. 5 is a perspective view of a solid or general purpose block.

Fig. 6 is a perspective view of a block formed in a plurality of longitudinally extending sections for a purpose to be later stated.

Fig. 7 is a sectional view through a wheel and an abrading block and holder, the abrading block being formed to true the edge of the wheel flange.

Referring to this drawing and particularly to Figs. 1 to 5, 10 designates the car wheel itself having the usual flange 11. The brake shoe 12 which constitutes a support for the abrading or truing block is formed with the ears 13 between which the brake rod 14 is pivoted in the usual manner. This brake shoe has the form of an arcuate plate having at its ends the inwardly ex-

tending flanges 15. These flanges are undercut at 16. The outer margin of the brake shoe 12 is provided with the longitudinally extending flange 17. This flange 17 at its extremities is outwardly extended, as at 18, beyond the outer faces of the end flanges 16, as shown particularly in Fig. 4. The brake shoe 12, as before stated, has the form of an arcuate plate but the inner face 19 of this shoe is not concentric to the periphery of the wheel but is curved on a greater radius 10 than the radius of the wheel 10.

The brake block 20 as disclosed in Figs. 3, 5 and 6 has its outer face conforming in curvature to the inner face 19 of the brake shoe, but its inner face 21 conforms to the curvature and has the same radius as the curvature and radius of the wheel 10, so that this block 20 fits closely against the periphery of the wheel 10, while the outer face of the block 20 fits closely against the curved inner face 19 of the brake shoe. The extremities of the block are notched at 22, the end walls of the notches extending outward and in opposite directions so as to fit within the notches 16, the end extremities of the block extending beyond the faces of the flanges 15, as shown clearly in Figs. 1 and 3. The block 20 bears at one side face against the flange 17 and is thus prevented from moving outward while the other face of the block bears against the flange 11 of the wheel 10. If desired, this side face of the block may be formed as shown in Fig. 7 at 23, so as to fit against and extend over the edge of the flange 11 so as to true this flange.

It will be seen that when the brake block is in place and the brake shoe in place, that the brake block is held between the flange 17 and the flange 11 of the wheel in the manner best shown in Figs. 2 and 7. The brake block 20 may be formed as illustrated in Fig. 5, of one piece of material and this may be either formed of an abrading material which will keep the wheel constantly trued, or of material which does not abrade the wheel. Preferably, however, this block 20 is of abrading material. By the term "abrading material", I do not wish to limit myself to the use of carborundum or like material, as these blocks 20 may be made of metal as, for instance, hardened steel and in this case would act to true the periphery of the wheel 10 and also act as a brake block. If these blocks are made of hardened steel or other metal, they would, of course, be considerably cheaper than if made of carborundum or like material.

Particular attention is called to the fact that this block 20 may be worn down to the dotted

30

35

line 24 shown in Fig. 3, so that the only portion of the block remaining would be the two pieces designated 25 in Fig. 3, which were engaged with the overhanging lugs or flanges 15. Thus almost 5 the entire block may be worn out before discarding the block for a new one. There would be no 10 wear upon the holder, of course, and the holder or shoe 12 would be ready for use again and again as long as the general equipment for the brake shoe would last.

In Fig. 6, I have illustrated a brake block formed of three sections *a*, *b* and *c*. These sections are to be made of different widths and different hardnesses to suit the car wheel upon 15 which the brake shoe is to be used. If the inner portion of the periphery of the wheel was higher than the outer portion of the periphery, an extra hard block would be used as the inside block and the soft block would be disposed in the middle and on the outside portion of the brake shoe. If the periphery of the wheel was higher at its 20 outside than at its inside, an extra hard block would be used on the outside and the soft block in the middle and on the inside. Thus the character 25 of the sections *a*, *b* and *c* which would be used would be determined by the necessities of any particular case. If the face of the wheel is wearing true, only one block such as shown in Fig. 5 would be used to cover the entire periphery 30 of the wheel. It will be obvious that when the brake shoe is in position upon the periphery of the car wheel that any movement of the blocks *a*, *b* and *c* will be prevented by the longitudinal flange 17 of the brake shoe and by the flange 11, thus any movement of the different parts or 35 sections is prevented.

To change the blocks, whether the single block shown in Fig. 5 or the sectional block shown in Fig. 6, is very easy and convenient. The shoe is 40 released from the brake mechanism, then the pieces of the old block removed and a new solid block or a new sectional block is slipped in and the shoe replaced. If the wheel is not wearing true and it is desired to abrade one portion of 45 the wheel periphery more than another portion, the sectional block shown in Fig. 6 may be used and sections of the proper hardness put in place. The changing of the blocks does not necessitate the use of any special tools nor any extra expense 50 and at the same time, time and money are saved in keeping the wheels at all times in good running order.

The structure shown in Fig. 7, as before stated, wears down or trues the edge of the flange 11 of 55 the wheel. A wheel wears down on its tread face. The flange ordinarily does not wear and thus the

flange projects out too much from the tread face of the wheel and is liable, under these circumstances, to split a switch. In order to eliminate this danger, it is necessary to put the wheel in a lathe and take a part of it off and if the brake shoe should extend out enough to catch or engage with the edge of the flange, this edge must be worked down to normal. By providing a brake block 20 of the form shown in Fig. 7 with a projecting portion 27 which extends over the edge of 10 the flange 11, the flange is continually abraded or trued in correspondence with the abrading or truing of the tread surface of the wheel. This keeps the flange down to normal and avoids the expense of putting the wheel in a lathe.

While I have described my structure as being particularly applicable to car wheels such, for instance, as the wheels on mine locomotives, mining cars, railroads, etc., it will be obvious that the invention may be used in any place where a 20 brake shoe is essential and particularly where it is desired to keep the face of the periphery of the wheel trued up at all times.

What is claimed is:

1. A brake shoe, comprising an arcuate body 25 plate having a flange at each end, the inner face of each flange being undercut, the inner face of the brake shoe being arcuate and having a curvature less than the curvature of a wheel to which the brake shoe is to be applied, and a brake block 30 having its outer face at its ends recessed complementary to the flanges of the brake shoe and interlocking therewith, the inner face of the block having a curvature the same as the true curvature of a wheel to which the brake block is to be 35 applied whereby to permit the brake block to be worn through at its middle portion to the inner face of the brake shoe.

2. A brake shoe, comprising an arcuate body 40 plate having a flange at each end, the inner face of each flange being undercut, the inner face of the brake shoe being arcuate and having a curvature less than the curvature of a wheel to which the brake shoe is to be applied, and a brake block 45 having its outer face at its ends recessed complementary to the flanges of the brake shoe and interlocking therewith, the inner face of the block having a curvature the same as the true curvature of a wheel to which the brake block is to be applied whereby to permit the brake block to be 50 worn through at its middle portion to the inner face of the brake shoe, the brake block being formed of a plurality of longitudinally extending sections differing in hardness.

CHARLES A. MALCOLM.
